UNITED STATES PATENT OFFICE.

CANDACE WHEELER, OF JAMAICA, NEW YORK.

DESIGN FOR HANGINGS, &c.

SPECIFICATION forming part of Design No. 16,337, dated October 13, 1885.

Application filed June 10, 1885. Serial No. 168,282. Term of patent 3½ years.

To all whom it may concern:

Be it known that I, CANDACE WHEELER, of 5
Jamaica, Queens county, Long Island, New
York, have invented a new and original De-
sign for Hangings, Upholstery, &c., of which
the following is a specification, reference be-
ing had to the accompanying drawing.

My invention relates to a new and original
design to be worked into or upon fabrics, pa-
per, &c., for use in hangings, upholstery, wall-
coverings, &c.; and it consists of the novel
grouping and configuration of figures herein
fully described and shown.

The drawing illustrates a face view of a
15 fabric having my new design.

The design consists in a natural but more
or less irregular combination of the pads, flow-
ers, and stems of the water-lily. The lily-
pads are disposed in irregular groups of two
20 or three, as shown, the letters *a* marking such
groups and their attached stems. In the
spaces between these groups are scattered
somewhat irregularly large circular lilies *b*,
both pads and flowers resting upon and sup-
25 ported by a net-work of intertwining and con-
tinuous stems, which is a leading feature of
my design. Each group contains one or
two pads fully open, some having their under
sides uppermost, and all showing plainly the

markings of their ribs and veins. In most of 30
the groups one lily-pad rests upon and half
conceals a second one. In some groups, as *c*,
there is one large lily-pad with its under side
fully seen, and near it two other pads, of which
either a side view or a foreshortened view is 35
had. In addition to the lily-pads, there is in
each group either one or two flowers, generally
opened wide and resting on or between the
pads, but sometimes only half opened and
projecting from underneath one of the pads, 40
by which it is partially concealed. Circular
blossoms are scattered in the spaces between
the groups, (see letters *b*,) some partially
opened, and half-closed lily-pads.

The different parts of the pads, flowers, and 45
stems are differently and variously outlined
and ornamented, as shown.

What I claim as new, and desire to secure
by Letters Patent, is—

The design for goods for hangings, uphol- 50
stery, &c., said design consisting of a repre-
sentation of the pads, flowers, and intertwined
stems of the water-lily, combined and arranged
substantially as shown and described.

CANDACE WHEELER.
